William Jordan Siegel, 814 E. Franklin Ave.,
Silver Spring, Md. 20901

Filed July 31, 1969, Ser. No. 18,486

Term of patent 14 years

Int. Cl. D13—02

U.S. Cl. D26—15

FIG. 1 is a front perspective view of a power unit for maintenance and repair of electronic equipment showing my new design; and

FIG. 2 is a rear perspective view thereof.

The characteristic feature of my design resides in the detailed arrangement of the front panel member, as best illustrated in FIG. 1.

I claim:

The ornamental design for a power supply unit for maintenance and repair of electronic equipment, as shown and described.
